Primary Examiner — Eric L Goodman*Assistant Examiner* — Sanjeev Paul(74) *Attorney, Agent, or Firm* — Alphapatent Associates, Ltd; Daniel J. Swirsky(57) **CLAIM**

The ornamental design for lighting spectacles, as shown and described.

DESCRIPTION

FIG. 1 is a rear view of lighting spectacles showing our new design;

FIG. 2 is a bottom view thereof;

FIG. 3 is a front view thereof;

FIG. 4 is a left view thereof;

FIG. 5 is a perspective rear view thereof;

FIG. 6 is a perspective front view thereof;

FIG. 7 is a right view thereof; and,

FIG. 8 is a top view thereof.

1 Claim, 8 Drawing Sheets---
